ATTORNEY.

UNITED STATES PATENT OFFICE.

GEORGE H. TAYLOR, OF RICHMOND, VIRGINIA.

LABEL-HOLDER.

1,327,298.

Specification of Letters Patent. Patented Jan. 6, 1920.

Application filed April 1, 1919. Serial No. 286,691.

To all whom it may concern:

Be it known that I, GEORGE H. TAYLOR, citizen of the United States, residing at Richmond, in the county of Henrico and State of Virginia, have invented certain new and useful Improvements in Label-Holders, of which the following is a specification.

This invention relates to a label holder and particularly to a clip construction adapted to be applied to a shelf or other supporting body to removably retain a price tag or label thereon.

The invention has for an object to provide a novel and improved construction of holder comprising a body portion having opposite flanges bent at an angle thereto and one of said flanges having an inwardly bent free edge to provide a gripping contact with a support.

A further object of the invention is to provide a label holder having inwardly bent angular flanges and a clasp pocket upon the body portion of the holder adapted to be tensioned toward the body as the flanges are separated.

Another object of the invention is to present an improved form of holder formed from a single blank having a looped portion of its body bent thereon to provide a clasp pocket and its opposite free edges bent at an angle to the body to form supporting and retaining flanges.

Other and further objects and advantages of the invention will be hereinafter set forth and the novel features thereof defined by the appended claims.

In the drawing—

Figure 1 is a perspective showing the holder applied to a shelf;

Fig. 2 is an end elevation of the holder; Fig. 3 is a front elevation thereof;

Fig. 4 is a plan of the blank from which the holder is formed;

Fig. 5 is a detail of one of the price labels;

Fig. 6 is a reverse view of the same;

Fig. 7 is an end elevation of the holder in reversed position; and

Fig. 8 is a similar view of a modified form of the invention.

Like numerals refer to like parts in the several figures of the drawing.

The numeral 10 designates the body of the holder adapted to contact with the outer edge of a shelf 11 or other support to which it may be applied. The upper edge of this body is formed with an inwardly bent sup-

porting flange 12 to rest upon the upper horizontal face of the shelf, while the lower portion of the body is bent upward to provide a holding clasp 13 and an intermediate pocket 14 to receive and retain a label or tag 15 of any desired character. Beyond the clasp 13 the material is bent downward at 16 and inward at 17 to form a retaining portion which is provided at its free edge with an angular inwardly disposed flange 18 adapted to effect a gripping contact with the under face of the shelf or body and resist a withdrawing movement of the holder. This construction also permits a removal of the holder upon the application of sufficient force when it is desired to change the position thereof. It will also be seen that when the substantially parallel supporting and retaining flanges are separated, as in the application of the holder to a shelf edge, the clasp portion is tensioned or forced toward the body of the holder to securely retain the inserted card or label in position.

The holder may be formed from a single straight edged blank of any desired bendable material, as shown in Fig. 4, and its construction permits the use of a light material such as tin, instead of resilient tempered steel, which greatly economizes in its manufacture and provides sufficient tension to retain the holder securely upon the body to which it is applied and the label within the pocket thereof. The device may be formed from such a blank by bending one edge thereof at a right angle upon the line 20 to form the flange 12. It is next bent upon itself upon the line 21 and then again upon itself at the line 22 to form the looped clasp portion 13. The portion beyond the clasp is then bent upon the line 23 at substantially a right angle thereto to provide the retaining flange 17, the free edge of which is bent inwardly and reversely at an obtuse angle on the line 24 to provide the gripping flange 18. While these several bending operations have been successively described, it will be obvious that they may be performed simultaneously by a suitable machine for that purpose.

The holder is particularly designed for use with changeable cards, tags, or labels, such as for price marking, and two or more of such cards may be assembled and securely held by the clasp which is placed under tension in the application of the holder to the shelf. These cards may be

of any desired material, preferably of light sheet metal with the characters suitably printed upon the opposite sides thereof. In the use of such cards the number thereof to be carried in stock may be greatly reduced and their selection and assemblage facilitated by printing or marking the odd numerals upon one face thereof and the even numerals upon the opposite or reverse face, as shown in Figs. 5 and 6. It will be evident that the person arranging the price label can thus very quickly select the numeral desired and insert it in the clasp of the holder.

15. If it be preferred to exhibit the label below the shelf containing the goods to be sold, the holder may be readily reversed in position upon the shelf and the cards retained therein in suspended position, as illustrated in Fig. 7. The holder may also be used when removed from a shelf to support a label or other announcement.

The holder when formed from a single piece of material has a limited degree of adjustment for application to shelves or supports of different thickness, and when it is desired to increase the range of this adjustment the holder may be formed in two parts, as shown in Fig. 8. In this modified form of the invention the body 25 is provided with a supporting flange 26 and has its lower portion bent upward at 27 to form the pocket and a member of the card clasp. The co-operating portion 28 is bent inward at 30 and provided with the outwardly bent free edge 31 to engage the under face of the support 11. By an adjustment of these members upon each other this form of the invention provides for its application to supports of a wide range of different thicknesses.

The application and operation of the holder will be apparent from the foregoing description and it will be seen that in the application of the supporting and retaining flanges upon a shelf they are forced apart which effects an inward tension upon the upper portion of the clasp to firmly secure the inserted card in position within the pocket. The gripping flange is so disposed as to resist a withdrawal movement of the holder and by its frictional contact with the surface of the shelf prevents accidental removal of the holder therefrom. This gripping contact is maintained even when the flanges are separated for a greater thickness of material at the edge of the support.

The formation of the holder from a single blank materially strengthens the flanges and increases their spring tension while occupying the minimum of space at the edge of the shelf. The card pocket and clasp thus formed provides a rounded edge to facilitate the insertion of any desired number of cards which are securely held under tension. The separation of the clasp caused by the inser-

tion of the cards produces a reacting tension upon the gripping flange and assists in retaining the holder in position.

The invention presents an efficient, simple and economically constructed form of label holder adapted to be readily applied and removed from a support and to securely retain the cards inserted in the clasp thereof. While the specific construction of the holder has been illustrated and described the invention is not limited thereto as defined by the following claims.

What I claim is:—

1. A label holder comprising a face portion having opposite parallel flanges at an angle thereto, and one of said flanges provided with a clasping pocket having a longitudinal free edge parallel with the face portion and an inwardly disposed free edge to form a gripping contact with a support. 80

2. A label holder comprising a body having a looped portion disposed parallel to the outer face thereof to form a clasping pocket and its opposite free edges extended at an angle to the body to provide supporting and retaining flanges connected to tension the pocket toward said body when separated. 90

3. A label holder having substantially parallel flanges for its retention upon a support, and a pocket parallel with the outer face of said holder having its upper portion constructed to clasp a label and connected to one of said flanges to be tensioned thereby toward the face when the flanges are separated. 95

4. A label holder comprising a body portion provided with opposite flanges disposed at an angle thereto, and a label clasping pocket upon said body connected to said flanges to be tensioned toward the body as 105 the flanges are separated.

5. A label holder comprising a body portion having an angularly disposed flange at one edge and a label pocket parallel with its outer face, a clasp member forming a portion of said pocket, and a retaining flange extended from said member to co-operate with the first mentioned flange and tension said member toward said face when the flanges are separated. 110

6. A label holder having substantially parallel flanges at its opposite edges for its retention upon a support and its body portion formed with a retaining pocket at its outer face disposed parallel thereto and connected to one of said flanges to be tensioned thereby toward the body as the flanges are separated. 120

7. A label holder comprising a body having one edge disposed at an angle thereto to form a supporting flange, an upwardly extending portion from said body parallel therewith to form a label clasping pocket having a downwardly and inwardly extending portion to provide a retaining flange 130

substantially parallel with the first mentioned flange and adapted to tension said pocket toward the body when the flanges are separated.

5 8. A label holder comprising a body having one edge disposed at an angle thereto to form a supporting flange, a looped upwardly extended portion parallel with said body to

provide a label clasping pocket having an angularly disposed retaining flange extending therefrom with a reversely disposed gripping free edge adapted to tension said pocket toward the body when the flanges are separated.

In testimony whereof I affix my signature. 15

GEORGE H. TAYLOR.
